(57) **CLAIM**

The ornamental design for a bicycle ABS brake, as shown and described.

DESCRIPTION

FIG. 1 is a perspective view of a bicycle ABS brake showing my new design.

FIG. 2 is a front elevational view thereof.

FIG. 3 is a rear elevational view thereof.

FIG. 4 is a right side view thereof.

FIG. 5 is a left side view thereof.

FIG. 6 is a top plan view thereof.

FIG. 7 is a bottom plan view thereof.

FIG. 8 is a perspective view similar to FIG. 1, but showing additional features in broken lines that form no part of the claimed design; and,

FIG. 9 is a rear elevational view similar to FIG. 3, but showing additional features in broken lines that form no part of the claimed design.

None of the features shown in broken lines in the drawing figures form part of the claimed design.
